UNITED STATES PATENT OFFICE.

CHARLES E. DAVIS, OF DAVENPORT, FLORIDA, ASSIGNOR TO GOODMAN MANUFACTURING COMPANY, OF CHICAGO, ILLINOIS, A CORPORATION OF ILLINOIS.

SCRAPER.

Application filed March 26, 1923, Serial No. 627,548. Renewed September 7, 1926.

This invention relates to improvements in draft operated scrapers used for gathering and transporting loose material and has for its principal object to produce an improved form of scraper capable of being initially deflected from its normal path of movement to gather loose material distributed over relatively wide areas. A further object is to provide an improved method of gathering 10 coal or the like from a mine room.

My invention may best be understood by reference to the accompanying drawings which illustrate one form in which my invention may be embodied. In the drawings:

Figure 1 is a rear perspective view of a scraper.

Figure 2 is a plan view of the scraper shown in Figure 1.

Figure 3 is a transverse section of the scraper.

Figures 4, 5, 6 and 7 are diagrammatic views illustrating the use and operation of my improved scraper in gathering coal adjacent the working face of a mine.

Referring now to details, the scraper comprises a body made up of two side walls 11^a, and 11^b, preferably diverging from the rear to the front end of the scraper, although other forms or shapes of scraper body may be provided if desired. The scraper is preferably bottomless, the wall 11^a, 11^b being provided with inwardly extending flanges 12^a, 12^b along their lower margins, to form cutting edges for engaging the material to be gathered. The walls 11^a, 11^b are pivotally connected by a hinge, which may be of any suitable form as for instance, it may comprise a pair of eyes 13, 13 on one wall 11^a and an intermediate eye 14 in the other wall 11^b, having a hinge pin 15 of any approved pattern extending therethrough. In the form shown, the side walls 11^a, 11^b are hinged centrally of the rear end, although under some conditions it may be desirable to vary the position of the hinged connection toward one side or the other of the scraper. The flange 12^a overlaps flange 12^b adjacent the hinged connection as shown in Figures 2 and 3. When in closed position flange 12^a engages a stop 16 formed on the upper face of the lower flange 12^b, and the said lower flange engages a stop 17 formed on the upper flange 12^a. A crossbar 18 is rigidly attached adjacent the forward end

of one side member, as for instance, the wall 11^b and extends across into position to engage the opposite side member 11^a. The free end of said crossbar is provided with a projection 19 adapted to register with an aperture 20 in wall 11^a and extend therethrough when the side walls are in closed position. When desired, the walls 11^a and 11^b may be rigidly connected together by securing the free end of the crossbar 18 to wall 11^a. For example, a pin 21 may be inserted in a hole 22 through the projection 19 when the latter is engaged in the aperture 20.

Draft means for the scraper comprises a head rope 24 connected to the forward end of the scraper by suitable means such as the terminals 25, 25, secured respectively to a forward end of walls 11^a, and 11^b, and a tail rope 26 connected to the rear end of the scraper by suitable means such as a ring 27 which in the form shown is connected to the intermediate eye 14 of the hinge.

The use and operation of the scraper above described will be understood by reference to Figures 4, 5, 6 and 7, illustrating its use in a mine room. In this instance the scraper is being used for gathering loose material adjacent the working face of the mine indicated at 30. A side wall or rib 31 meets the working face 30 at an angle, forming a corner as shown in these figures. In Figure 4 a pile of loose material has been deposited on the floor adjacent the working face, the toe or forward edge of this pile being indicated at 32. The portion of the loose material adjacent the side wall 31 is cleared away for a purpose that will presently appear. The scraper is installed for reciprocable movement along the working face in the usual manner well known to those familiar with mining methods. The tail rope 26 is trained over a sheave or guide 34 fixed by a jack or similar means against the side wall or rib 31 and adjacent the working face 30 substantially as shown in the diagram. In the loading operation the scraper is pulled rearwardly by the tail rope into position substantially shown in Figure 4. Now, before starting the forward movement of the scraper, the operator may move the side 11^a of the scraper pivotally away from the side 11^b into a position shown in Figure 5, in which it will be seen that the forward edge of the wall 11^b is pulled about 110

- and positioned in the cleared area in the corner of the room. In this position it will be observed that the hinged portions 11^a and 11^b are spread apart so that the terminals 5 25, 25 connected to the head rope are substantially in a straight line. The scraper is ready for its initial forward movement, this movement being commenced by placing tension upon the head rope 24. The operator 10 may then direct the hinged portion 11^a so to engage the pile of loose material, the pull on the head rope being applied directly to this hinged portion. A further pull on the draft line tends to close the hinged walls, but 15 due to the greater resistance exerted by the material engaged by the hinged portion 11^a, the other hinged portion 11^b will be pulled inwardly toward the working face, as indicated in Figure 6. The movement of the 20 scraper will therefore be initially deflected from its normal path of forward movement in line with the head rope, as indicated in Figure 7. The scraper thus has a tendency to hug the working face in initially gathering its load. When a load is gathered it is 25 pulled forwardly to the point of discharge and then returned for another load, whereupon the operation above described is repeated. In each loading operation, the 30 scraper may be initially directed toward the working face as in the first instance. Similarly, the scraper may be directed to the opposite side if desired, by movement of the wall 11^b.
- 35 Although I have shown and described one form in which my invention may be embodied, it will be understood that the construction and arrangement of the parts may be varied without departing from the spirit 40 and scope of my invention. I do not therefore wish to be understood as limiting myself to the specific construction illustrated herein excepting as specifically limited in the appended claims.
- 45 I claim as my invention:
1. A scraper provided with forwardly extending walls having hinged closed connection at their rear ends whereby said walls may be pivotally moved laterally respective 50 to each other, a flexible connecting member having its terminals each connected with one of said walls, and a drag line connected to the central portion of said flexible connecting member.
  - 55 2. A scraper provided with forwardly extending walls pivotally connected at their rear ends whereby said walls may be moved laterally respective to each other, means 60 limiting the inward movement of said walls,

a flexible connecting member having its terminals each connected with one of said walls, and a drag line connected to the central portion of said flexible connecting member.

3. A scraper provided with forwardly extending walls pivotally connected at their rear ends whereby said walls may be moved laterally respective to each other, means limiting the inward movement of said walls, and a drag line connected to a flexible connecting member having its terminals each connected with one of said walls, the total length of 65 said flexible connecting member being greater than the distance between its respective points of connection with the side walls when the latter are in a closed position.

4. A scraper provided with forwardly extending walls pivotally connected at their rear ends whereby said walls may be movable laterally respective to each other, means limiting the inward movement of said walls, a drag line having connection with a flexible connecting member having its terminals each connected with one of said walls, and a tail line connected with said scraper.

5. A scraper provided with forwardly extending walls pivotally connected together at the rearward end of said scraper to swing outwardly respective to each other, means limiting the inward movement of said walls, a flexible connecting member connecting the outer extremities of said walls together and limiting the outward movement of said walls, and a drag line operatively connected to said flexible connecting member.

6. A scraper provided with forwardly extending walls pivotally connected at their rear ends whereby said walls may be moved laterally respective to each other, means limiting the inward movement of said walls, a flexible connecting member operatively connecting a drag line with said movable walls, and means for rigidly connecting said walls together.

7. The method of deflecting a drag line scraper during its initial forward movement under tension, which consists in shifting a movable side wall portion of said scraper laterally into position to engage a portion of the material to be gathered, and thereafter causing tension to be placed on the drag line, whereby the resistance of the material engaged by said movable wall portion will cause the entire scraper to be initially deflected at an angle to the drag line.

Signed at Chicago, in the county of Cook 115 and State of Illinois, this 23rd day of March, 1923.

CHARLES E. DAVIS.
